UNITED STATES PATENT OFFICE.

EERT U. IWWERKS, OF KANSAS CITY, MISSOURI.

SOUND-REPRODUCING MECHANISM.

Application filed June 5, 1922. Serial No. 563,946.

To all whom it may concern:

Be it known that I, EERT U. IWWERKS, a citizen of the United States, residing at Kansas City, in the county of Jackson and State of Missouri, have invented certain new and useful Improvements in Sound-Reproducing Mechanism; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to sound reproducing machines, and particularly to a machine in which the undulations in a phonographic record transmit vibrations to a sounding element through the medium of a stylus, a vibrator bar connected to a plurality of strings, and the said strings connected longitudinally to a resonator, a body about the size and shape of a cello, which, through the combination above given, audibly delivers sounds of great volume and clear and mellow tone, and achieves this with perfect instrumental balance, eliminating that peculiarly characteristic phonographic tone, and, furthermore, reproducing sounds without any extra adjustable device from both vertical and horizontal undulations on phonographic records with like accuracy.

The novel construction of the invention will be apparent by reference to the following description in connection with the accompanying drawings, in which—

Fig. 1 is a perspective view of a sound reproducing mechanism constructed in accordance with my invention.

Fig. 2 is a longitudinal, sectional view through the sound box, the strings being shown in elevation.

Fig. 3 is a fragmentary perspective view showing the strings and part of the stylus bar, and means for connecting the stylus bar to the strings.

Fig. 4 is a detail perspective view of one of the adjusting nuts for the strings.

Fig. 5 is a detail view of one of the bridges, part of the sound box and the strings being shown in section, and

Fig. 6 is a view partly in elevation showing the anchor plate connected to a flexible finger at right angles to the vibrating bar forming a fulcrum for the vibrating bar, the bar being shown in section.

Referring now to the drawings by numerals of reference:

1 designates a cabinet containing suitable mechanism for rotating the turntable 2. 60 Upon the turntable may be located a disk 3 provided with the usual grooves having undulations corresponding to the recorded vibrations of the particular selection transmitted thereto. 65

The sound reproducing mechanism is shown as consisting of a standard 4 on which is a sleeve 5 adapted to be adjusted with respect to the standard through the medium of a collar 6 and a set screw 7. The sleeve 5 carries an arm 8 having a lateral supporting member 9, to which is secured by an articulated joint 10 a sound box 11. The sound box is shown as conforming structurally to a stringed instrument body, for example, a violin. 75

At the respective ends of the body are posts 12 and 13, which may be secured to the body in any suitable manner. The ends of the posts or anchor bars 12 and 13 project beyond the face of the sound box body and have perforations to receive a plurality of strings, for example, such as is designated by the reference numerals 14, 15 and 16. Each of the strings has one end fastened to one of the posts 12 or 13 and the other end provided with a thread to receive an adjusting nut whereby tension can be provided for the strings. In the illustration the strings 14 and 16 are fastened to the post 13 and project through the post 12 so that their threaded ends may receive adjusting nuts 17 and 18. The string 15 is fastened to the post 12 and it projects through the post 13 and is provided with an adjusting nut 19. A section of one of the adjusting nuts, for example, 18, is shown in Fig. 2 as provided with a square recessed end 20 to receive the end of a clock key so that the nut can be turned on its string and thereby cause the end of the nut to bear against one of the posts 12 or 13 to draw the string taut, the amount of tension, of course, depending upon the screwing up or the unscrewing of the nut 18. 95

The strings are supported by end bars 21 and 22 and by intermediate bridges 23, 23' and 23'', which may be adjusted between the bars 21 and 22. The strings are all of the same size and the bridges 23, 23' and 23'' have string-receiving seats or projections 14', 15' and 16' respectively, offset with re-

105

22

spect to one another so that each bridge supports only one string and since the bridges are positioned on different longitudinal parts of the sound box, it will be apparent that each string will be pitched differently. The strings are connected to a vibrating bar 24, having a bifurcated end 25 to provide a slot 26 in which the strings may be received, the bifurcated portion of the vibrating bar 10 being fastened to the strings by connecting and spacing screws 27, 28 and 29 which maintain the strings in spaced relation and also assist in clamping the bifurcated portion of the vibrating bar 24 to them. The free end of the vibrating bar is rigidly fastened to a finger 30 on a plate 31, rigidly connected to the sound box, the finger providing for the torque of the vibrating bar 24 and allowing relative vibration thereof as it not only constitutes a support but also a slight fulcrum medium for the bar. With the construction shown herein, the device is adapted for records having either vertical or horizontal undulations. At the lower end of the bar may be secured a stylus 32 to be received in the grooves of the record. On the cabinet 1 I may provide a sound box rest 1', which may be of any preferred construction adapted to receive the body of the violin-shaped sound box when it is tilted on its fulcrum 10 to raise the stylus needle off the record 3.

As heretofore stated, the strings are preferably of different pitches and they can be tuned by the adjusting nuts 17, 18 and 19. If all the strings were of the same pitch and the stylus were vibrated by the undulations a number of vibrations corresponding to the pitch vibrations of the strings, then there would be a tone exceeding in volume the normal. However, normalization is maintained by providing the strings of varying pitches, whereby all the vibrations are neutralized, because the vibrating bar will never be in absolute vibratory synchronism with any one string. In practice, I find this arrangement provides a very clear tonal reproduction of the selection transcribed on the record.

What I claim and desire to secure by Letters Patent is:

1. A sound reproducing mechanism comprising a sound box, a plurality of strings of different pitches arranged longitudinally of the sound box, a stylus bar connected to all of the strings, and means for individually tensioning the strings. 55

2. A sound reproducing mechanism comprising a sound box, a plurality of strings connected to the sound box, the strings being of different pitches, and a stylus arm rigidly connected to all of the strings, the stylus arm having a bifurcated end clamped to the strings. 60

3. A sound reproducing mechanism comprising a sound box, a plurality of strings supported by and in spaced relation with the sound box, a separate bridge for each string, the bridges being in spaced longitudinal alignment, a stylus bar connected to all of the strings, and means for rigidly connecting the stylus bar to the sound box. 70

4. A sound reproducing device comprising a stylus for engaging undulations of a record, a vibrating bar, to the lower end of which the stylus is secured, said vibrating bar being bifurcated at its upper end, a plurality of strings clamped in the bifurcated portion of the bar and means for audibly reproducing the vibrations of said strings, 80 caused by engagement of the stylus with the undulations of a sound reproducing record. 75

5. A sound reproducing device comprising a stylus for engaging undulations of a sound reproducing record, a vibrating bar, to the lower end of which the stylus is secured, said vibrating bar being bifurcated at its upper end, a plurality of strings securely clamped in the bifurcated portion of the bar, a sound box, means for supporting the strings in spaced relation on the sound box and separate bridges for each string, said bridges transmitting the sound by vibration to the sound board of the sound box when the stylus is vibrated by the undulations of a sound reproducing record. 95

In testimony whereof I affix my signature.
EERT U. IWWERKS.
